UNITED STATES PATENT OFFICE.

CHARLES F. SPERY, OF CHICAGO, ILLINOIS, ASSIGNOR TO CHICAGO UTILITIES MANUFACTURING COMPANY, A CORPORATION OF ILLINOIS.

RADIATOR.

1,191,359.

Specification of Letters Patent. Patented July 18, 1916.

Application filed March 4, 1915. Serial No. 11,954.

To all whom it may concern:

Be it known that I, CHARLES F. SPERY, a citizen of the United States, and a resident of the city of Chicago, in the county of Cook and State of Illinois, have invented a certain new and useful Improvement in Radiators; and I do hereby declare that the following description of my said invention, taken in connection with the accompanying sheet of drawing, forms a full, clear, and exact specification, which will enable others skilled in the art to which it appertains to make and use the same.

My invention relates generally to improvements in radiators, and it consists, essentially, in the novel and peculiar combination of parts and details of construction, as hereinafter first fully set forth and described and then pointed out in the claims.

In the sheet of drawing already referred to, which clearly discloses in detail the preferred mode of constructing my newly invented radiator, Figure 1 is a front elevation of a device of the class described, in which is embodied my invention, and it is here explained that the hexagonal outlines therein represent horizontal air or cooling passages and are drawn to substantially full size scale, while the outline of the radiator frame is on reduced size and merely sketched in to denote the relationship of the various parts. Fig. 2 is a horizontal section at line 2—2 of Fig. 1. Fig. 3 is a vertical section at line 3—3 of Fig. 2. Fig. 4 is a horizontal section at line 4—4 of Fig. 3. Fig. 5 is a plan of one of a multiplicity of peculiarly bent light sheet metallic strips, which, when properly fabricated, constitute duplicate units employed in the carrying out of my invention. Said plan is approximately full size, except as to length, which length may be extended to whatever height it may be desired to construct the radiator. Fig. 6 is an edge view of Fig. 5. Fig. 7 is a longitudinal, vertical section at line 7—7 of Fig. 5, on a double enlarged scale. Fig. 8 is an edge view of one of the duplicate units composed of one of the strips illustrated in Figs. 5 and 6 rebent upon its self with its free ends joined together as hereinafter more fully referred to. Fig. 9 is a section at line 9—9 of Fig. 8. Fig. 10 is a detail denoting the appearance of one end of the unit shown in Fig. 8, after the strip of Figs. 5 and 6 has been bent upon

itself and before the operation has been completed. Fig. 11 is a section of a fragment at line 11—11 of Fig. 1.

Like parts are indicated by corresponding symbols or characters of reference in all the figures of the drawing.

One of the objects of my invention is the construction of a radiator for cooling the circulating water from gasoline engines in what is generally and broadly termed the cellular type of radiator; the particular aim in my invention being the provision of the greatest possible radiating surface compatible with the volume of water to be cooled, and correlated to this, are features of construction which renders it possible that the heat radiating from the water needs to be transmitted through only one thickness of metal before being acted upon by the cooling medium. It is well known that in the cellular type of radiators the structure thereof requires a multiplicity of lapped joints, and double thickness of sheet metal, which not only means extra cost of material, but, loss of efficiency in the cooling surface as well. In my invention these disadvantages are eliminated.

Another object of my invention is to construct a radiator from truly duplicate units, whereby the size of the radiator may be increased or decreased in size by the simple addition or subtraction of such units.

A further object is to construct each of the units referred to from a single strip of long, narrow, thin sheet metal, so bent, rebent, formed, and fabricated mechanically as to produce a series of closely spaced transverse air passages, each of which passages is connected to adjacent ones whereby an air circulation in both a horizontal and a vertical direction may be created throughout each unit. And in connection with these units are formed continuous offset flanges which, co-acting with the flanges on adjacent units form sinuous, substantially vertically disposed water passages between said units, in which the direction of flow of the water is constantly changed and agitated, whereby the entire body of water flowing through said passages is brought into contact with the cooling surfaces.

Other novel features and details of construction are included in my invention as will more fully appear, and to more fully

understand the same, reference is now made to the drawing, in which—

A, Figs. 1 and 3 denotes the assembled radiator in its entirety, while the completed units thereof are indicated as B in Fig. 8. These units are made from thin strips of sheet brass or copper approximately .005 inch thick and of a width equaling the depth decided upon for the radiator. This raw material is received from the mill in large coils containing 1000 feet or more and these coils are relatively mounted adjacent a suitable stamping press provided with a series of step by step dies and feeding means establishing a constant though intermittent feed of the material through said dies. The first step in the dies aforesaid is to shape the strip into a succession of semi-hexagonal, parallel, transverse corrugations 10, the said die at the same time forming U-shaped passages, 11 between adjacent semi-hexagons, which passages in this initial operation extend the entire width of the strip B'. But as the feeding of the strip proceeds, the next stage or step of the die aforesaid is encountered, which step enlarges the size of the semi-hexagons 10 along the margins of the strip, forming semi-hexagonal enlargements or flanges 12, and at the same time pinches together the metal at the ends of the U-shaped passages as at 13 converting the passages into closed ended pockets 11 as it were, and it is here explained that these pockets form component parts of the water passages in the completed radiator as hereinafter described. The flanges 12 it will be observed lie in planes parallel to the planes of the sides of the semi-hexagon 10, along the outer edges of the strips, and gradually merge into said sides by beveled partitions 14, whereby there is produced at either end of the semi-hexagons 10 an outwardly flaring mouth 15 as indicated in Fig. 6. It is now to be noted that the flanges 12 coact with like flanges on other units B to afford a jointure therebetween, and, the flanges forming larger semi-hexagons than the semi-hexagons 10, a zig zag channel 16 is produced throughout the length of the strips in an obvious manner. While the die process producing the enlarged semi-hexagons is taking place, the said die also successively forms an indentation 10^c in the lower wall 10^b of each pocket 11, so as to establish communication between adjacent semi-hexagons 10.

The process of shaping the strip B' as already described proceeds continuously until the entire length of material has been unrolled from the coil already referred to. But in conjunction with the die press there is arranged a longitudinally adjustable shearing device whereby the strips B' may be cut after being shaped into any desired length. Thus if it be desired to construct a plurality of units B each possessed of for instance six complete hexagonal passages 10^a, the strip B' is cut as of a length of fifteen semi-hexagons 10 as seen in Fig. 6. In like manner if units having thirty hexagonal passages be desired, the length of the strip B' will be sixty three semi-hexagons. The vertical and upwardly inclined walls of the outer semi-hexagons are re-shaped into vertical walls 17 and 17^a, and the latter thereof is formed with an offset 17^b for purposes hereinafter described. The medial semi-hexagon indicated at X Figs. 5 and 6 is then placed on the horn of a suitable horn die and bent into an acorn shaped structure 18, shown in Fig. 10. This process results in a bending, toward each other of the portions of the strip B' lying on either side of the medial semi-hexagon X until the lower walls 10^b of the water pockets 10 of one of said portions are in alinement and also in contact with like walls of the other of said portions, at which time the end walls 17 and 17^a will be found to align with each other, with the offset 17^b overlapping the wall 17. The acorn shaped structure 18, Fig. 10 is lastly flattened together as seen at 18^a Fig. 6 to effect a firm and easily soldered joint at that point, and the application of a brazing torch or a soldering iron at the jointure of the walls 17 and 17^a will insure a union of those parts in an obvious manner.

The structure thus far described in detail constitutes a radiator unit shaped from a single strip of sheet metal; it is possessed of a plurality of adjacent, parallel, transverse, hexagonal air passages 10^a, connected together by channels 10^d, Figs. 3 and 9, and having funnel shaped inlet or outlet mouths 15^a to reduce the frictional resistance of air entering therein, it being understood that the thickness of the bridge between said hexagonal passages at the entrance and exit thereof is only .010 inch or twice the thickness of the strip B'. This is an essential of my invention. In all the cellular type of radiators known to me, there is a plane surface of decided width located between each air passage, whereby the velocity of flow of air through the passages is greatly decreased and the cooling efficiency thereof distinctly lessened. The fact that the horizontal passages 10^a are connected together by the vertical channels 10^d insures a free circulation of air not only in a horizontal but a vertical direction as well, whereby the entire developed shape of the unit as a whole becomes effective as cooling surfaces. It will be also observed that both the upper and lower surfaces of the unit B are provided with zig zag channels 16, from the lower apices of which extend the pockets 11, and, said channels and pockets are components of water channels 16^a, created when said units are assembled as described be-

low: To convert the units B into a radiator A, an assembling frame is first provided. This frame is an open rectangular structure which may be likened to the chase in which assembled type is locked before being fastened in a printing press. This chase or open frame is of a depth possibly one half inch less than the width of the units B and has along one inner edge an adjustable metallic plate, which is acted upon by adjusting set screws passing through said frame. One unit B is placed in this frame against said adjusting plate. Another unit B is now placed against the first, but this unit is reversed as it were, with the extension 18^a extending in a direction opposite that of the like extension on the initial unit. In this manner, the apices 20 of the flanges 12 of the first unit contact with the lower apices 20 as 13 produced by the pinching together of the end walls of the passages 11. In other words the zig zag contour of the second unit nests into the like zig zag of the initial unit B. Thus nesting these two units together with their marginal flanges 12 in close contact, creates water passages 16^a of zig zag outline with a plurality of spaced pockets 11 as already described. Additional units B are placed in the frame adjacent each preceding one, the extensions 18^a alternately projecting upwardly and downwardly, as the case may be, until the said frame is filled, whereupon the set screws in the frame are manipulated until all the flanges 12 of the plurality of units are in intimate contact with adjacent flanges. The assembled structure is then dipped into a bath of molten solder and the like until a tight and firm union of all the flanges 12 is accomplished. The frame is now turned over and the opposite side of the structure likewise dipped, after which the frame is removed and the plurality of units, now essentially a single unit is ready for placing into the radiator frame. This frame may be of any desired construction including an upper tank 30 for the reception of the heated water from the hydro-carbon or other motor, and a lower tank 31 for receiving the water from the cooling passages 16^a, and it is not therefore necessary to go into a detailed description of said framing, except to point out that the extensions 18^a projecting alternately upwardly and downwardly perform novel and important functions in connection with the upper tank 30 and lower tank 31. Referring to Fig. 11 it will be noted that these extensions are not the full length of the passages 10, but are shortened at both ends at 18^b so that the side walls 40 and 41 may rest squarely upon the upper edges of the plurality of units, flush with the outer edges thereof. In this manner the upper face of the units forms the bottom of the upper tank 30, and a single solder seam at 42 and

43, Figs. 1 and 11 serves to prevent any external leakage of water. The said walls are likewise soldered to the extensions 18^a at 44 and 45 thereby forming lateral stiffness for the upper tank in an obvious manner, and it may be added that the lower tank is similarly treated.

I have hereinbefore disclosed the preferred mode of practising my invention, but I reserve the right to make such and any changes as might occur to one skilled in the art to which this invention appertains, or to make any and all such alterations as may be permitted under the doctrine of equivalents.

Having thus fully described my invention I claim as new, and desire to secure to myself by Letters Patent of the United States:—

1. A radiator section including a plurality of vertically disposed, duplicate units of irregular contour, there being vertically spaced apart, horizontally extending, shallow water pockets in the opposing faces of each of said units, said units partially nesting into each other and joined together, there being substantially vertical water ways between adjacent units, following the contour of said units, said water ways being in communication with said water pockets, there being horizontal air passages through each of said units directly adjacent said water pockets, said horizontal air passages being connected together by vertical channels extending between said oppositely disposed water pockets, whereby a horizontal and a vertical flow of air is permitted through said units.

2. A radiator section including a plurality of vertically disposed duplicate units of irregular contour, there being vertically spaced apart, horizontally extending, shallow water pockets in the opposing faces of each of said units, said units partially nesting into each other and joined together, there being substantially vertical water ways between adjacent units, following the contour of said units, said water ways being in communication with said water pockets, there being horizontal air passages through each of said units directly adjacent said water pockets, said horizontal air passages being connected together by vertical channels extending between said oppositely disposed water pockets, whereby a horizontal and a vertical flow of air is permitted through said units, the inlets and outlets of said horizontal passages being substantially funnel shaped, to permit a freer entrance and exit of air.

3. A radiator including an upper tank, a lower tank and a plurality of duplicate units of irregular contour connecting the same, there being alternate upwardly and downwardly extending ribs on alternate units projecting into the upper and lower tanks respectively, to stiffen the marginal walls

4
 of said tank; there being vertically spaced apart, horizontally extending, shallow water pockets in the opposing faces of each of said units, said units partially nesting into each other and joined together, there being substantially vertical water ways between adjacent units, following the contour of said units, said water ways being in communication with said water pockets, there being 5 horizontal air passages through each of said units directly adjacent said water pockets, said horizontal air passages being connected together by vertical channels extending between said oppositely disposed water pockets, 10 whereby a horizontal and a vertical flow of air is permitted through said units.
 4. A radiator including an upper tank, a lower tank and a plurality of duplicate units of irregular contour connecting the same, 15 there being alternate upwardly and downwardly extending ribs on alternate units projecting into the upper and lower tanks respectively, to stiffen the marginal walls of said tanks; there being vertically spaced 20 apart, horizontally extending, shallow water pockets in the opposing faces of each of said units, said units partially nesting into each other and joined together, there being substantially vertical water ways between adjacent 25 units, following the contour of said units, said water ways being in communication

with said water pockets, there being horizontal air passages through each of said units directly adjacent said water pockets, said horizontal air passages being connected together by vertical channels extending between said oppositely disposed water pockets, whereby a horizontal and a vertical flow of air is permitted through said units, the inlets and outlets of said horizontal passages being substantially funnel shaped, to 30 permit a freer entrance and exit of air.

5. As an article of manufacture, a single, continuous, sheet metallic strip bent back upon itself medially of its length and having its free ends joined to each other, said strip being provided with a plurality of equally spaced transverse corrugations extending the entire width of said strip and intervening walls between said corrugations, 40 the height of said walls being greater at the longitudinal margins of said strip than intermediate thereof, said walls having contact with opposite walls when said strip is so rebent and joined.

55 In testimony whereof I have set my hand in the presence of two subscribing witnesses.

CHARLES F. SPERY.
